UNITED STATES PATENT OFFICE

ERNA BLATTMANN, BY MARRIAGE NOW ERNA BLATTMANN VOLSK, OF HOLLYWOOD, CALIFORNIA

DESIGN FOR AN EYESHADE

Application filed March 25, 1930. Serial No. 35,018. Term of patent 14 years.

To all whom it may concern:

Be it known that I, ERNA BLATTMANN, by marriage now Erna Blattmann Volsk, a citizen of Switzerland, residing at Hollywood, in the county of Los Angeles and State of California, have invented a new, original, and ornamental Design for Eye Shades, of which the following is a specification, reference being had to the accompanying drawing, forming a part thereof.

Fig. 1 is a side elevational view of an eye shade showing my new design.

Fig. 2 is a top plan view of the eye shade.

I claim:

The ornamental design for an eye shade, as shown.

ERNA BLATTMANN.
